William Kieckois Design for a Stove.

Fig. 2.

Des. 144₁₁

William Hickok, New York
Seth's Patent (Design No 144), dated August 14th 1847
Ante dated 12th February 1847.

The schedule referred to in these Seth's Patent and making part of the same.

To all whom it may concern: Be it known that of William Hickok, of the City, County, and State of New York, have invented a new design for a stove, which is described as follows, reference being had to the annexed drawings of the same, making part of this specification.

Figure 1. is a plan of the front plate of the stove, shewing a series of parallel sunken and raised panels arranged in alternate order, each ornamented with a flower pot and vine in base relief of the design delineated in the annexed drawings.

Figure 2. is a plan of one of the side plates ornamented with raised panels and flowers of designs such as those represented in the annexed drawings.

All the plates near the angles are ornamented in a peculiar and similar manner after the design as delineated in the annexed drawings.

What I claim as my invention & desire to secure by Seth's Patent is the design for a stove as set forth in the accompanying drawings and written description of the same.
